UNITED STATES PATENT OFFICE

166,764

INTERVAL TIMER

Frederick Lux, Middlebury, and Helmut D. Beerbaum, Wolcott, Conn., assignors to The Lux Clock Manufacturing Company, Inc., Waterbury, Conn., a corporation of Connecticut

Application June 9, 1951, Serial No. 15,477

Term of patent 14 years

(Cl. D42—7)

To all whom it may concern:

Be it known that we, Frederick Lux, a citizen of the United States, residing at Middlebury, Connecticut, and Helmut D. Beerbaum, a citizen of the United States, residing at Wolcott, Connecticut, have jointly invented a new, original, and ornamental Design for an Interval Timer, of which the following is a specification, reference being had to the accompanying drawing, forming part thereof.

Fig. 1 is a front view of an interval timer showing our new design.

Fig. 2 is a side view of the same.

Fig. 3 is a bottom plan view of the same.

We claim:

The ornamental design for an interval timer, substantially as shown.

FREDERICK LUX.
HELMUT D. BEERBAUM.
